Inventor:
Helen R. Mondy.

UNITED STATES PATENT OFFICE.

HELEN R. MONDY, OF ATLANTIC CITY, NEW JERSEY.

ELECTRICAL BRUSH.

1,393,635.

Specification of Letters Patent. Patented Oct. 11, 1921.

Application filed February 12, 1921. Serial No. 444,621.

To all whom it may concern:

Be it known that I, HELEN R. MONDY, a citizen of the United States, residing at 609 North Indiana avenue, Atlantic City, in the 5 county of Atlantic and the State of New Jersey, have invented a certain new and useful Improvement in Electrical Brushes, of which the following is a specification, such as will enable those skilled in the art to 10 which it appertains to make and use the same.

The object of this invention is to provide an improvement in hair brushes for brushing and drying the hair after shampooing 15 or after a person has gotten the hair damp or wet.

This brush can be carried easily in a small hand bag and used at any time where electricity is available.

20 My invention is fully described in the following specification, of which the accompanying drawings form a part.

Figure 1 is a plan of my apparatus embodying my invention showing part of the 25 bristle plate broken away.

Fig. 2 is a diagrammatic view in section of the apparatus which I employ and showing the electric wiring and heating unit therefor.

30 Fig. 3 is a section on the line 3—3 of Fig. 1; similar reference characters designate similar parts throughout the drawing.

In Fig. 1 of the drawings I have shown a hair brush A consisting of a body portion 35 A', a bristle plate a, and bristles a' of metal and a handle H of wood. Part of the bristle section is broken away for the sake of clearly illustrating the construction as shown in Fig. 1.

40 In Fig. 2 of the drawings, I have shown a metal core C running through the center of the handle and the body of the brush. Through this metal core runs a twin conductor c which extends up through the handle to the body of the brush where it contacts with the heating unit. This heating unit consists of a small length or coil of high resistance wire which becomes red hot 45 due to the current passing through it and 50 which heats the bristles.

At the end of the handle H is an opening o, adapted to receive the plug p. To the plug is attached insulated wire w which connects with the screw plug. This screw plug can 55 be connected to an electric fixture not shown.

With the screw plug thus connected up with

the current, the latter carries the heat to the body of the brush and to the bristles through the metal plate to which they are detachably attached. When the bristles have become sufficiently heated, the plug may be detached or the electric current cut off by means of the screw plug. 60

In Fig. 3 of the drawings, I have shown in cross section the concave metal plate 65 which is perforated for the passage of the bristles and which is secured to the bristle face of the brush by having the edges of the plate fit into dovetail seats s formed by turning over the edge of the brush. 70

It will be apparent that when duly heated in the manner above described my brush is adapted for quick detachment from the electric connection on a wall, chandelier, or elsewhere, by unscrewing the screw plug p', and 75 can then be used for treating the hair of a customer when seated at any convenient place in a room, or shop, or when lying down at a place remote from the connection. 80

My invention is well adapted for the purpose for which it is intended and is a very useful and convenient device.

Having thus described my invention, what I claim and desire by Letters Patent to secure is:

An electric brush for drying hair comprising a hollow body having a metal plate of convex surface and fitted into the open face of the body and held in place by the 90 overturned edge of the body; bristles fitted into the convex face of the metal plate with their free outer ends forming the working surface of the brush; a tubular handle adapted to be screwed into the end of the body of the brush, a metal core extending through the handle into the body of the brush, a plug secured in the outer end of the handle, and a heating element formed of resistance wires passing through the plug into the core 100 to heat the body of the brush and the convex plate carrying the bristles, a second plug to which the outer ends of the resistance wires are fastened and which is adapted to be screwed onto a wall socket to obtain the current for transmission to the bristles, all as and in the manner substantially as described and shown. 105

In testimony that I claim the foregoing as my invention I have signed my name this 110 10th day of February, 1921.

HELEN R. MONDY.
